UNITED STATES PATENT OFFICE.

ROBERT L. COONEY, OF ATLANTA, GEORGIA.

STATIONARY FIRE-EXTINGUISHER SYSTEM.

1,075,015.

Specification of Letters Patent.

Patented Oct. 7, 1913.

Application filed November 29, 1909. Serial No. 530,468.

To all whom it may concern:

Be it known that I, ROBERT L. COONEY, a citizen of the United States, residing at Atlanta, in the county of Fulton and State of Georgia, have invented new and useful Improvements in Stationary Fire-Extinguisher Systems, of which the following is a specification.

This invention relates to new and useful 10 improvements in stationary fire extinguisher systems of a type in which the power or influence developed by the activity of a pneumatic medium at ordinary temperature is utilized as a motive force to directly effect 15 the operative movement of a mechanical controlling element of fire extinguisher agent supply means.

The invention involves the combination 20 with a system wherein the operation may be produced by an impulse which is derived from a static pressure of a means for developing another and independent impulse 25 from an outside source and which produces the same operations as the impulse derived from the static pressure. The particular advantage of such a combination resides in its provision for dual control, the present arrangement being operable at will without 30 regard to the presence or absence of the charging pressure and being of utility in the emergency of the absence of the charging pressure, a circumstance which would otherwise defeat the operation of the automatic system.

35 The pulsation or equivalent action of elastic fluid may advantageously be of "positive" character. The word "positive" as used in this connection and throughout the specification, does not have the meaning 40 which it usually has in the mechanical sciences but is intended to describe a pressure which operates expansively or by positive projection.

The invention proposes as a novel adjunct 45 an acid bottle having a surrounding drainage chamber for a purpose to be described.

Embodiments of the invention are illustrated by way of example in the accompanying drawings wherein—

50 Figure 1 is a central longitudinal sectional view of a system in which the present invention is carried out. Fig. 2 is a similar view of an alternative apparatus preserving the basic principles stated. Fig. 3 is a fragmentary sectional view of an alternative structural detail. Fig. 4 is a sec-

tional view showing one form of an acid bottle provided with a drainage chamber. Fig. 5 is a similar view showing an alternative form of acid bottle provided with a drainage chamber.

Similar characters of reference designate corresponding parts throughout the several views.

In the example shown in Figs. 1 and 2, 65 there is disclosed an automatic system which forms the basis of my co-pending application, Serial No. 540,661, operable by a pneumatic impulse and which includes a tank 1, a distributing pipe 2 provided with sprinkler heads or equivalent devices, and a shell 3, communicating with the distributing pipe and fitted into the end of the tank. A barrel 4 is connected to the shell 3 and projects into the tank 1, being therein provided with 70 a depending pipe, as 5, through which the fire extinguisher agent flows to the distributing system.

The tank 1 contains the fire extinguisher agent supply means, e. g. a chemical mixing apparatus involving an invertible acid bottle which, in this instance, constitutes the aforesaid movable mechanical element. This bottle, designated by the numeral 6, is in the present example pivotally supported 75 off and below center on a bracket, as 7.

A plunger 8 is fitted in the shell 3 and is operatively connected to the acid bottle. Toward this end the plunger is provided with a rod 9 which projects axially through 80 an opening 10 in the end of the barrel 4 and is connected to the acid bottle by a chain, as 11. The plunger 8 constitutes a means operable by the pneumatic impulse previously referred to, for effecting the overturning of the acid bottle. The motive force 85 for operating the plunger 8 in the embodiment thus far described, is preferably derived from a maintained charging pressure. This pressure is put in the distributing 90 pipe 2, in the shell 3, and in the tank 1. The pressure in the pipe 2 and in the shell 3 is a controlling or "dominant" pressure, and the pressure in the tank 1 is an operating "servient" pressure and is normally 95 held in restraint by the "dominant" pressure but becomes active when the latter falls consequent to the opening of a sprinkler head to produce an operative movement of the plunger 8 and therewith the inversion of 100 the acid bottle. To prevent the escape of gas from the tank when the plunger has

105

110

completed its outward movement, the rod 9 is provided with a conical head, as 12, which seats conformably in the aforesaid opening 10.

- 5 Any suitable means may be employed to charge the system with a pressure vehicle, and the latter may be of any desired character, *e. g.* air or a gas fatal to combustion. For example, a suitable hydraulic pump A 10 is shown conventionally in Fig. 2, for this purpose.

In the apparatus described it is essential that the pressure in the distributing pipe and in the tank 1 be kept equal or at balance 15 degrees. For this purpose a by-pass connection, as 13, may be provided, the same involving a pipe which connects the tank 1 and pipe 2 and in which is fitted a diaphragm 14 having a pin hole aperture 20 which provides for the normal equalization of the pressures in compensating for slight leakages but does not allow any material degree of pressure to escape from the tank 1 when the pressure in the pipe 2 is suddenly and materially reduced consequent to 25 the opening of a sprinkler.

The improvements which form the basis of the present invention may be, as previously stated, advantageously combined 30 with a system of automatic control, an example of which has been described, and alternative forms of such a combination are herein disclosed.

An example of the present improvement, 35 as shown in Figs. 1 and 2, involves a pipe, as 15, which is equipped with devices, as 16, for creating or producing the elastic-fluid pulsation. A pump, as shown in Fig. 1, or a cylinder of compressed air, as shown 40 in Fig. 2, may be mentioned as examples of such a device.

In the arrangement shown in Fig. 1, the pipe 15 is employed in connection with a means, additional to the piston 8, for overturning the acid bottle, such a means including 45 a piston, as 17, which works in a barrel, as 18, and has a plunger, as 19, which projects through one end of the barrel and against which the acid bottle rests. The barrel 18 has an upward extension which is set into 50 the upper side of the tank, and to which is coupled a pipe section 20. The latter branches from a pipe 21 which is joined to the pipe 15.

55 Any of the devices 16 may be operated to create a pulsation of air which produces an operative movement of the piston 17 and the resultant inversion of the acid bottle. The developed pressure moves the plunger 60 8 to the outer end of the cylinder 3.

Except for the variations to be detailed in the following paragraph, the arrangement shown in Fig. 2 is similar to the arrangement shown in Fig. 1.

65 In Fig. 2, the pipe 15 is shown as joined

to the by-pass 13 in such a manner that the pressure from the cylinder 16 enters the upper portion of the tank 1 through the by-pass and acts on the piston 8, forcing the same outwardly and thereby effecting the 70 inversion of the acid bottle in the manner explained. In this arrangement the piston 17 and its adjuncts are not employed.

The pulsation creating and utilizing arrangements of Figs. 1 and 2 are, when combined with the maintained pressure apparatus, primarily intended for use in the emergency incident to the absence of a charging pressure in the system. 75

The present arrangement provides for 80 the use of a combined pressure gage and alarm as an adjunct of the automatic system and for the application and assemblage of this device in a novel relation and manner. The combined pressure gage and 85 alarm is shown in Fig. 1 and consists of a U tube, as 22, mounted on a suitable graduated base 23 and having one leg connected to an extension of the pipe 21. The tube 22 contains a body of mercury or its equivalent, as 24, which coöperates with platinum contacts 25, 26 and 27. In order to put the U tube in communication with the system so that it may be subject to the influence of the 90 charging pressure therein, the pipe 21 is connected to the pipe 2 by a by-pass, as 28, in which is fitted an apertured diaphragm 29. The pressure in the system normally holds the body of mercury out of contact 100 with the contact 26. In case the pressure rises sufficiently, *e. g.* in case of a fire, or for other reasons, the body 24 changes its position so as to engage the contact 27 and thereby to close a circuit and sound an 105 alarm.

If, by reason of leakage, the charging pressure is lost, the body 24 shifts to engage the contact 26, thereby closing a circuit by which devices (not shown) are operated to 110 give notice of the loss of pressure. A slight pressure, however, holds the body of mercury out of contact with the contact 26. The graduations on the base 23 indicate at all times the degree of charging pressure 115 present in the system.

Fig. 3 discloses an alternative detail in which a coniform nozzle 30 is substituted for the piston 17 and is connected to a pipe, as 18^a. When the nozzle 30 is used, it is 120 preferred to employ a cylinder of compressed air as the source of the pulsation, and a suitably located, normally sealed valve, as 18^b is provided to produce the pulsation. The nozzle 30 terminates in close 125 proximity to the upper end of the acid bottle, and the force of the concentrated jet of fluid delivered by this nozzle is sufficient to move the acid bottle past its center of gravity.

In Figs. 4 and 5, there is shown a novel 130

acid bottle construction, the distinguishing feature of which is the provision of a supplemental chamber, open at its upper end and preferably surrounding the acid bottle. In Fig. 4 the acid bottle is indicated by the numeral 31 and is provided with a surrounding jacket, as 32, open at its upper end and, in the constructions wherein the acid bottle is invertible, provided with trunnions 33. Where the acid is confined in a solution tank, in a separate container, there is an absorption of moisture, which eventually causes the mixture to overflow the bottle, some of the acid being thereby lost and the strength of the alkaline solution weakened. By the use of what for convenience has been termed the "drainage" chamber, the acid is not lost, and the solution is not weakened, since any excess mixture due to the cause noted, overflows into the jacket 32 and not into the body of solution. In Fig. 5, the jacket, as 32^a, is disposed above the bottle, as 31^a, surrounding the neck 31^b thereof. The bottle, in this instance, is provided with trunnions, should these be necessary. In this connection, it should be noted that the jacket is of particular advantage for the purpose indicated, because in the use of a lead bottle such as is ordinarily employed, it is practically impossible to provide a visible mark or gage line to indicate the proper level. By the use of the present bottle which may be filled to the top, a predetermined and exact amount of acid may be used.

Having fully described my invention, I claim:

1. In a fire extinguisher system, the combination with a tank containing a body of liquid, a distributing pipe leading therefrom, and fire extinguisher agent supply means including a movable pressure operated controlling element arranged in the

tank, the tank and the distributing pipe serving to contain elastic fluid under pressure, and the fluid in the tank becoming active when the fluid in the distributing pipe is exhausted to produce the operative movement of the element, and additional optionally operable means exterior to, and independent of the tank for immediately developing an elastic fluid pulsation to produce the operative movement of the element.

2. In a fire extinguisher system, the combination with chemical mixing means including an acid bottle of means for maintaining a dominant elastic fluid pressure, means for maintaining a servient elastic fluid pressure which operates automatically and positively to cause the acid bottle to discharge its contents when the dominant pressure is reduced and additional optionally operable means for developing a fluid pressure pulsation to cause the acid bottle to discharge its contents.

3. In a fire extinguisher, an acid bottle forming a part of chemical mixing apparatus and an overflow chamber associated with the acid bottle into which an excess mixture incident to the absorption of moisture by the acid may drain.

4. In a fire extinguisher, an acid bottle forming a part of chemical mixing apparatus and a jacket surrounding the acid bottle and open at its upper end, the jacket providing an overflow chamber into which an excess mixture incident to the absorption of moisture by the acid may drain.

In testimony whereof I have hereunto set my hand in presence of two subscribing witnesses.

ROBERT L. COONEY.
